CONNECTOR BLOCK

Benny Morris Bennett, Harrisburg, and Linn Stephen Lightner, Camp Hill, Pa., assignors to AMP Incorporated, Harrisburg, Pa.

Filed Nov. 19, 1968, Ser. No. 14,527

Term of patent 14 years

Int. Cl. D13—03

U.S. Cl. D26—1

Fig. 2

Fig. 6

FIG. 1FIG. 2FIG. 3FIG. 5FIG. 7

FIG. 1 is an overall perspective view, partly broken away, of a connector block showing our new design;

FIG. 2 is a front elevational view of the connector block of FIG. 1;

FIG. 3 is a top plan view of the connector block;

FIG. 4 is a bottom plan view thereof;

FIG. 5 is a side elevational view as seen looking from the right of FIG. 3 and rotated 90 degrees clockwise;

FIG. 6 is a side elevational view looking from the left of FIG. 4 and rotated 90 degrees counter clockwise; and

FIG. 7 is a rear elevational view of the connector block.

The connector block is shown broken away to indicate indeterminate length.

We claim:

The ornamental design for a connector block, substantially as shown and described.
